UNITED STATES PATENT OFFICE.

WILLIAM E. WHITE, OF TOLEDO, OHIO, ASSIGNOR OF ONE-HALF TO HARRY A. COE, OF TOLEDO, OHIO.

RADIATOR.

1,101,109.

Specification of Letters Patent. Patented June 23, 1914.

Application filed June 13, 1913. Serial No. 773,378.

To all whom it may concern:

Be it known that I, WILLIAM E. WHITE, a citizen of the United States, and a resident of Toledo, in the county of Lucas and State of Ohio, have invented a certain new and useful Radiator; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to radiators of the class intended particularly for use in connection with the engine cooling systems of automobiles, but is not restricted to such use as it may be used in any connection for which it may be adapted or appropriate.

The object of my invention is the provision of an improved radiator of the character described, which is simple and inexpensive in its construction, composed of a minimum of parts, and has its air cells separated from the water passages by substantially plain sheets of metal, thus reducing the liability of leakage and enhancing the efficiency and commercial value thereof.

Further objects and advantages will be apparent from the following description.

The invention is fully described in the following specification, and while, in its broader aspect, it is capable of embodiment in numerous forms, a preferred embodiment thereof is illustrated in the accompanying drawings, in which,—

Figure 1 is a front elevation of a radiator embodying the invention with the lower portion thereof broken away. Fig. 2 is an edge elevation of a radiator section with a portion broken away and with parts thereof in separated position. Fig. 3 is a side elevation thereof. Fig. 4 is a cross-section on the line $\alpha-\alpha$ in Fig. 5, and Fig. 5 is an isometric view of a portion of a radiator.

Referring to the drawings, 1 designates a radiator embodying the invention, which is of the cellular type and has the customary water receiving and dispensing chambers in the upper and lower portions thereof, respectively, such chambers being connected by a plurality of water passages

or conduits which are spaced by air cells or passages, as is well understood in the art.

The water passages or conduits are formed by arranging a plurality of smaller units or sections side by side with portions separated from each other to form intermediate water spaces or passages. Each of the units of the radiator, all of which are identical in construction, comprises the opposing side members 2-2 and the intermediate member 3, which latter co-operates with the side members to form two vertical rows of air cells 4 extending from front to rear of the unit.

The member 3 preferably comprises a single piece of sheet-metal, which is shaped to form a plurality of vertically spaced cross-pieces 5 and intermediate spacing parts 6 of Z-bar form, which have their edges integrally connected to the respective edges of the cross-pieces 5. Or in other words the member 3 extends downward between the side members 2, 2 and is provided in vertically spaced relation with sets or pairs of oppositely projecting loops which form the cross-pieces of the member 3. It will be noted that the looping of the member 5 in this manner makes the cross-pieces of double thickness to strengthen the same.

Each side 2 of a unit is inwardly looped at its upper and lower ends, as at 7, with the terminal portions thereof turned inward over such loop in spaced relation thereto to provide an inwardly opening recess 8 for fitting over the respective edge of the upper and lower cross-pieces 5 of the member 3, as indicated at 9. The members of a unit having been assembled together in this manner the upper and lower ends thereof are dipped into a soldering solution to secure the members together. The front and rear edges of the side members 2 are outwardly offset from their body portions to provide the edge shoulders 10 for coacting with the corresponding offset edges 10 of a laterally adjoining unit to form a vertically-disposed water passage or space 11 between the major portions of the adjoining sections, the upper and lower ends of which passages are open to the receiving and dispensing chambers, respectively, of the radiator. When a plurality of units have been placed together in assembled relation the front and rear

- sides thereof are dipped in a soldering solution to solder the units together and close any water escape openings which might be present between the abutting edges thereof.
- 5 It is preferable to provide the body portion of each side 2 of a unit with a plurality of vertically spaced corrugations or embosses 12, which extend from front to rear and are disposed intermediate the cross-pieces 5 of 10 the core member 3, the corrugations extending outwardly relative to the water passages so as not to effect a restriction thereof. The ends of the cross-pieces or loops 5 are laterally broadened to fit into the off-set 15 portions 10 of the respective side members 2 to brace such portions as is apparent.
- It is evident that a rapid cooling of the water in its passage between the upper and lower chambers of the radiator is possible 20 by constructing the cellular portion thereof, as above described, as each water passage is provided with an individual row of air cells at each side thereof instead of a single row of cells being disposed between successive 25 water passages, as is commonly the case in radiators of this class; and also that the liability of leakage from the water passages is reduced to a minimum, as the side walls of such passages are of substantially plain 30 integral form, as distinguished from the class of radiators in which the walls of the water passages are outwardly looped to form air cells between adjoining passages. Furthermore it is evident that the only points 35 where leakage would be apt to occur in a radiator of this construction would be at the front and rear sides of the cellular construction at the points where the shoulders 10 abut, which points are easy of access and 40 can be resoldered or repaired without necessitating the tearing apart of the radiator.
- I wish it understood that my invention is not limited to any specific construction, arrangement or forms of the parts except in 45 so far as such limitations are specified in the claims.
- Having thus described my invention, what I claim as new, and desire to secure by Letters Patent, is,—
- 50 1. In a radiator, a section comprising opposite side members and an intermediate member, said intermediate member having oppositely projecting portions serving to space the side members apart and to co-operate therewith to form a plurality of 55 rows of cells, the side members having their ends looped to form inwardly opening re-
- cesses for receiving registering oppositely projecting portions of the intermediate member. 60
2. In a radiator, a plurality of adjoining sections each having opposed sheet-metal sides which are provided with horizontally-spaced vertically-extending outwardly-offset portions for coacting with like portions of 65 the sides of adjoining sections to form vertical water passages and having their opposite ends looped to form inwardly opening recesses, and a sheet-metal member disposed between the sides of a section and being of 70 zig-zag form to provide oppositely projecting portions for spacing the sides and forming a double row of air cells therebetween which extend entirely through the radiator, some of said member portions fitting into 75 and being secured to the end recesses of the side walls.
3. In a radiator, a plurality of adjoining sections each comprising sheet metal side members with vertically extending portions 80 thereof outwardly offset to coact with similar portions of the sides of adjoining sections to form water passages therebetween, and a sheet metal member disposed between the side members of a section and co-operating therewith to form a double row of air cells therebetween extending from the front to the rear of the radiator, said intermediate member having upper and lower end portions which interengage and form close 85 joints with registering portions of the respective side members.
4. In a radiator, a plurality of adjoining sections each comprising three pieces extending from front to rear of the section and 90 forming side walls and an intermediate member, the intermediate member forming a vertical web substantially parallel to and in spaced relation to the side walls and at intervals forming oppositely projecting ledges 95 which abut at their outer edges against the side walls and co-operate therewith and with the web portion to form a double row of air cells, and the side walls co-operating with the side walls of adjoining sections to form vertically disposed water passages. 100
- In testimony whereof, I have hereunto signed my name to this specification in the presence of two subscribing witnesses. 105
